(57) **CLAIM**

The ornamental design for a surface pattern for pump for liquids, as shown and described.

DESCRIPTION

FIG. 1.1 is a front left perspective view of a pump for liquids.

FIG. 1.2 is a front right perspective view of the pump for liquids,

FIG. 1.3 is a front view of the pump for liquids,

FIG. 1.4 is a rear view of the pump for liquids,

FIG. 1.5 is a right side view of the pump for liquids,

FIG. 1.6 is a left side view of the pump for liquids,

FIG. 1.7 is a top plan view of the pump for liquids, and

FIG. 1.8 is a bottom plan view of the pump for liquids.

The broken lines in the drawings illustrate portions of the pump for liquids that form no part of the claimed design. The portions of the drawings shown in gray (i.e., reduced opacity) form no part of the claimed design.

1 Claim, 8 Drawing Sheets
